C. L. GOODRUM

TELEPHONE EXCHANGE SYSTEM

Filed Sept. 30, 1920

Inventor:
Charles L. Goodrum
by J. Roberts Atty.

UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 30, 1920. Serial No. 413,856.

To all whom it may concern:

Be it known that I, CHARLES L. GOODRUM, a citizen of the United States, residing at New York, in the county of New York, State of New York, have invented certain new and useful Improvements in Telephone-Exchange Systems, of which the following is a full, clear, concise, and exact description.

10 This invention relates to improvements in telephone systems and has particular reference to a selector switch used in systems employing machine switching.

It has been customary, in selector switches 15 of known construction, to effect the change-over operations by the use of slow-releasing relays.

An object of the present invention is to provide improved means for eliminating the 20 use of slow relays in the operation of a selector switch.

In accomplishing the above object, the invention provides two switching devices which cooperate to transmit impulses for 25 operating the switch, one of said devices being responsive to the connection of a calling substation to the selector switch and to impulses transmitted from said substation, while the other device is responsive only to 30 the movement of the variably operable impulse sender from its normal position when actuated to transmit said impulses.

The drawing diagrammatically illustrates a preferred embodiment of a circuit 35 arrangement for carrying out the invention.

It is believed that the invention will be best understood from the following detailed description of operation.

When a subscriber at substation 1 removes 40 his receiver from its switchhook to initiate a call, the line switch, conventionally shown at 2 and which may be of any desired construction, is operated to seek the terminals of a trunk associated with an idle selector switch. Upon the engagement of the brushes 45 of the line switch with the terminals 3, 4 and 5 of an idle switch, a circuit is established extending from grounded battery through the left-hand winding of differential line relay 6, side switch wiper 7 in position 1, terminal 4, brush 8, the apparatus 50 at substation 1, the impulse springs 9 of the variably operable sender 10, brush 11, terminal 3, the side switch wiper 12 in position 1, the winding of pulsing relay 13, and

the right-hand winding of relay 6 to ground. Relay 6 is arranged so as not to respond to the current flowing through this metallic circuit, but relay 13 is energized to open its normal contacts.

The subscriber at substation 1 now proceeds to manipulate the impulse sender 10 to transmit impulses corresponding to the first digit of the required number, and upon the initial movement of said sender from its normal position the off normal springs 14 of the sender are closed to establish a circuit from a ground branch including a resistance through said springs 14, the substation apparatus, brush 8, terminal 4, side switch 70 wiper 7, and the left-hand winding of relay 6 to grounded battery. Differential relay 6 responds to current flowing through this circuit, and, in closing its front contact, prepares a circuit for the primary stepping 75 magnet 15 of the selector switch. The return movement of the sender 10 causes the alternate opening and closing of the impulse spring 9 to interrupt the line circuit extending through the pulsing relay 13, 80 which responds to each interruption. The resistance connected to spring 14 prevents the short-circuiting of the impulse relay 13. Inasmuch as relay 6 remains energized as long as the sender is off normal, a circuit will 85 now be established, upon each deenergization of relay 13, extending from ground through the armature and front contact of relay 6, the inner armature and contact of relay 13, the side switch wiper 16 in position 1, and the winding of the primary stepping magnet 15 to grounded battery. The magnet 15 operates in the well-known manner to step the brushes 17, 18 and 19 over the terminals of trunks to which the switch 90 has access. Upon the initial energization of relay 6, a circuit is established for escape magnet 20, extending from grounded battery through the winding of said magnet, the side switch wiper 21 in position 1, and the front contact and armature of relay 6 to ground. Magnet 20 energizes but the usual escape mechanism is arranged to prevent movement of the side switch wipers from position 1 95 until said magnet releases. With the termination of series of impulses transmitted from the substation, sender 10 is again restored to normal, opening the off normal springs 14, which causes the deenergization of relay 6. Relay 13, however, remains 100

105

110

energized. The release of relay 6 opens the energizing circuit for escape magnet 20, which thereupon releases to move the side switch wipers from position 1 to position 2. 5 A self-interrupting circuit is immediately established for the secondary stepping magnet 22, traceable from grounded battery through the winding, armature and contact of said magnet, the armature and contact of 10 magnet 20, and the side switch wiper 23 in position 2, to ground. Magnet 22 operates the switch in its secondary or trunk hunting movement and causes the brushes thereof to engage the terminals of the selected group 15 of trunks in seeking an idle one in said group. The idle condition of a trunk is denoted by ground upon the test terminal 24, and upon the engagement of the brushes of the switch with the terminals of the first 20 idle trunk encountered, a circuit is established for escape magnet 20, extending through the side switch wiper 21 in position 2, and brush 19, to ground on the test terminal 24. The escape mechanism of magnet 20 is, in this instance, adjusted to move the side switch wipers of the switch from 25 position 2 to position 3 upon the energization of magnet 20. It is thus apparent that the instant an idle trunk is encountered, 30 magnet 20 energizes to permanently open the self-interrupting circuit of magnet 22 whereupon the switch will be brought to rest upon the terminals of the seized trunk.

If at any time before the movement of 35 the side switch wipers from position 2, the subscriber at substation 1 should abandon the call, the circuit for pulsing relay 13 will be opened at the switch hook contacts and this relay will release. With relay 6 in its 40 normal condition a circuit will then be established for the release magnet 25, extending from grounded battery through the winding of this magnet, the side switch wiper 26 in positions 1 or 2, the off normal contact 27, which is closed upon the initial 45 movement of the switch from its normal position, the back contact and outer armature of relay 13, and the back contact and armature of relay 6 to ground. Magnet 25 is 50 energized and closes a locking circuit for itself through its contact and armature, whereupon the off normal contact 27 will be opened and the magnet 25 released.

The movement of the side switch wipers of the switch into position 3, by the second 55 energization of magnet 20 extends the telephone line of substation 1, through to the next succeeding switch which, if desired, may 60 be of the same construction and arrangement as the one shown in the drawing. The transmission of further impulses from substation 1 operates any succeeding switches to extend 65 the calling subscriber's line to the called line, in a manner well understood. The

movements of the side switch wipers into position 3 also causes the release of pulsing relay 13, whereby this relay, together with relay 6, is now in normal position. With the side switch wiper 28 out of position, 70 ground from the armature and back contact of relay 6 is removed from the multiple test terminal 5 of the trunk associated with the seized switch and causes the same to test busy to any other line switch. 75

At the termination of the conversation, the switches, succeeding the one shown in the drawing, are released in any manner well-known in the art by the replacing of the receiver upon its switch hook at the called 80 substation. Ground being again applied to the test terminal 24, engaged by brush 19, causes the energization of the release magnet 25, through the side switch wiper 26 in position 3. The release magnet is again energized and locked to return the switch to normal, as previously described. 85

What is claimed is:

1. In a telephone system, a variably operable impulse sender, a selector switch, 90 means responsive to impulses from said sender for operating said switch, and means consisting of only two relays at said selector switch for transmitting the impulses from said sender to said operating means, one of said relays being responsive only to the movement of said sender from its normal position.

2. In a telephone system, a variably operable impulse sender, a selector switch, means responsive to impulses from said sender for operating said switch, and means consisting of only two relays at said selector switch for transmitting the impulses from said sender to said operating means, one of said 100 relays being unaffected by the seizure of said selector switch.

3. In a telephone system, a variably operable impulse sender, a selector switch, means responsive to impulses from said sender for operating said switch, and means consisting of only two relays operable to transmit impulses from said sender to said operating means, one of said relays being operated 110 only while the sender is off normal.

4. In a telephone system, a telephone line, a variably operable impulse sender, a selector switch for extending said line, means for operating said switch, a switching device at said switch responsive to the initiation of a 120 call on said line and to impulses transmitted by said sender for controlling the operation of said operating means, and another switching device cooperating with the first named switching device and responsive only 125 to the movement of said sender from its normal position.

5. In a telephone system, a telephone line, a variably operable impulse sender, a selector switch for extending said line, means 130

for operating said switch, a pulsing relay at said switch responsive to the initiation of a call on said line and to impulses transmitted by said sender for controlling the operation of said operating means, and a differential relay cooperating with said pulsing relay and responsive only to the movement of said sender from its normal position.

10. 6. In a telephone system, a telephone line, a variably operable impulse sender, a selector switch for extending said line, means for

operating said switch, a pulsing relay at said switch responsive to the initiation of a call on said line and to impulses transmitted by said sender for controlling the operation of said operating means, and a differential relay in series with said pulsing relay and operable only when said sender is moved from its normal position.

15. In witness whereof, I hereunto subscribe my name this 27th day of September A. D., 1920.

CHARLES L. GOODRUM.
